DIVIDER ATTACHMENT

George J. Young, Depew, N. Y.

Application February 22, 1944, Serial No. 523,387

1 Claim. (Cl. 33—149)

1

This invention relates to attachments for machinist's dividers and particularly to attachments capable of converting such dividers into various kinds of calipers.

In the prior art various attempts have been made to construct tools or instruments which serve the purpose of both dividers and calipers. Attachments have also been proposed for converting tools or instruments from one of the above types to another. In general, the combination tools previously proposed have been awkward and cumbersome and generally inaccurate as precision measuring instruments. Attempts to render them more accurate usually result in tools or instruments whose conversion from one type to another is too difficult or time consuming to be profitable. Further, combination tools in this field frequently are more costly to produce than the several separate tools which they are intended to replace. In the case of attachments, likewise, their mode of connection with the tool proper has generally been such as to be either lacking in accuracy or in facility of application.

The present invention provides a simple unitary device which may be applied to a divider leg in a simple and speedy manner to convert such leg into a caliper leg. The nature of the attachment of the present invention is such that it may be almost instantaneously applied to a divider leg with respect to which it will inherently retain a relatively fixed and accurate position. Further, according to the present invention, the attachment is such that it may be selectively applied to a caliper leg in a variety of relative positions. In this way, a given pair of dividers may be selectively converted into inside or outside calipers and, further, both the inside and outside calipers so formed may be of various kinds, as will appear in greater detail from a consideration of the detailed description which follows in conjunction with accompanying drawing.

While a single specific embodiment of the attachment of the present invention is described in detail and illustrated in the drawing it is to be understood that this is done merely by way of example and that the spirit and scope of the invention are not limited otherwise than as defined in the appended claim.

In the drawing:

Fig. 1 is a longitudinal cross sectional view of a preferred form of the divider attachment of the present invention.

Fig. 2 is an elevational view thereof taken at right angles to Fig. 1.

Fig. 3 is an elevational view of a pair of ma-

2

chinist's dividers fitting with a pair of caliper-forming attachments like the one shown in Figs. 1 and 2.

Fig. 4 is a fragmentary elevational view showing the attachments applied in an alternative manner for outside caliperizing; and

Fig. 5 is a fragmentary elevational view showing the attachments applied in an alternative manner for inside caliperizing.

Throughout the several figures of the drawing like characters of reference denote like parts and the attachment of Figs. 1 and 2 is designated generally by the numeral 10. Such attachment comprises essentially a tubular upper portion 11 and an offset lower terminal portion 12 which forms a caliper foot. The tubular upper portion 11 provides a socket 13 which may directly receive a divider leg in the manner illustrated in Fig. 3, where a conventional machinist's dividers is shown at A. If the caliper feet 12 are directed toward each other as shown in full lines in Fig. 3, the dividers are converted to outside calipers, whereas if the feet are directed outwardly as shown in dot and dash lines in Fig. 3, the dividers 26 are converted into inside calipers.

The transverse cross sections of the legs of machinist's dividers are generally oblong, at least they are so at short distances up from their points. For this reason the socket 13 of each attachment may be oblong in cross section, whereby when the attachment is applied as in Fig. 3 for either an outside or an inside caliperizing operation, there will be no possibility of rotation of the foot on the divider leg.

It is desired that the attachment be applicable to divider legs in the oblique manner illustrated in Fig. 4, so that various outside caliperizing operations may be performed without interference by the legs of the dividers proper. To this end the tubular portion 11 of each attachment 10 is provided with the pair of oblique openings 15 and 16 which, considered as a unit, taper lengthwise at approximately the degree which the divider legs proper generally taper. In other words, referring to Fig. 1, the opening 16 is smaller than the opposite opening 15. It will be noted from Fig. 2 that the openings 15 and 16 are likewise oblong, and this is for the same reason as was stated in connection with a discussion of socket 13. It will be noted from Figs. 1 and 2 that the tubular portion 11 of the attachment 10 is slit lengthwise as at 18, the slits preferably extending to a point below the openings 15 and 16. At least the tubular portion 11 of attachment 10 is

preferably formed of a resilient material to cause

the attachment to grip a divider leg to which it is applied, whether it be applied lengthwise as shown in Fig. 3 or obliquely as shown in Fig. 4. To produce this result it is obvious that both the socket 13 and the oblique passages 15 and 16 or at least portions thereof, must be initially somewhat less in dimension than the part of the divider leg which the attachment is to grip when in assembled position.

Fig. 5 is a view similar to Fig. 4 which shows the attachments applied obliquely for inside caliper for various purposes as for instance when an inside diameter can be reached only by projecting the instrument through a considerably smaller inside diameter. This arrangement also increases the maximum inside diameter which may be measured with a given instrument.

A great deal of the efficacy of the present attachment is attributable to the facility with which it may be applied and the wide variety of positions and combinations that may be effected. By merely removing the attachment of any one of Figs. 3, 4, and 5, a variety of hermaphrodite calipers are provided. By applying one leg for inside caliper and the other leg for outside caliper, odd-leg calipers are provided, such as

are used in measuring shoulder distances on flat work, boring half round, etc. By applying an attachment to one leg lengthwise and the other obliquely, both being directed for outside caliper, keyhole calipers are provided.

Some of the less used forms of calipers or combination caliper-dividers are not found in the average machinist's or mechanic's assortment of tools because of the cost of acquiring a large variety of special purpose tools. They are desirable but the fact that they are not used frequently leads the machinist or mechanic to adopt a makeshift for occasional uses. The obvious simplicity and versatility of the present attachment places at the disposal of machinists and other mechanics the means for accomplishing many special-purpose caliper and dividing operations.

What is claimed is:

20 A caliper attachment for dividers and like instruments comprising a split tubular portion of resilient material providing an expansible socket for receiving and resiliently gripping the terminal portion of a divider leg, and a laterally offset caliper foot rigidly carried by said tubular portion.

GEORGE J. YOUNG.
